METHOD OF AND APPARATUS FOR
ATTACHING SOLES TO SHOESFrancis L. Brandt, Bridgeport, Conn., assignor
to United Shoe Machinery Corporation, Flem-
ington, N. J., a corporation of New Jersey

Application January 26, 1942, Serial No. 428,236

4 Claims. (Cl. 12—17)

This invention relates to methods of and apparatus for attaching soles to shoes, the invention being particularly useful in the shoe repair trade.

Heretofore it has been customary to attach soles and half soles to shoes by means of pyroxylin cement in the repair trade and in commercial shoe production. The equipment for this work is quite elaborate, requiring a large number of lasts or other shoe supports, several presses and a good deal of floor space besides a high labor cost and loss of time waiting for the cement to set. Moreover, in repair work, after the cement on the sole and shoe is activated, the sole has to be tacked on the shoe bottom and then placed under pressure. While under pressure the active cement is apt to be forced out from between the shoe and sole and to get on the upper, requiring an expensive cleaning operation.

Objects of this invention are to provide a novel method of cement sole attachment whereby the above-indicated disadvantages of prior methods will be avoided.

In one aspect the invention comprises a method of cement-attaching soles to shoes which consists in providing a shoe and its sole with pressure-responsive cement on their attaching faces, locating the sole on the shoe, supporting a localized area only of the inner face of the insole, applying pressure to a corresponding area at the opposite side of the outsole to cause adhesion of the outsole to the shoe in said area and repeating the operation at successive localized areas about the periphery of the shoe. This application of pressure to force the insole and outsole together at localized areas about the periphery of the shoe results in a very firm attachment of the sole to the shoe when a strong cement is employed. A suitable cement for the purpose is a chloroprene cement such as that disclosed in Letters Patent of the United States No. 2,061,296, granted November 17, 1936, in the name of Walter H. Wedger. After cement of this kind is applied to the attaching faces of the shoe and sole and allowed to dry for a short time, it reaches a condition in which, while dry to the touch, it will stick when pressed upon a similarly cemented surface. With the shoe and sole in this condition, the sole may be readily "spotted" on the shoe, the preliminary sticking of the cemented surfaces being sufficient to hold the sole in position. The shoe is then treated by applying heavy pressure to localized portions of the margin of the insole inside the shoe and

corresponding portions of the outsole. This treatment, being carried on about the periphery of the shoe and sole, results in the firm attachment of the sole to the shoe, obviates the necessity of tacking the shoe and sole together and eliminates the use of shoe supports or lasts as well as pressure-applying pads. Since the cement at the time of attachment is incapable of flowing under pressure, the uppers remain clean, resulting in saving of time and improved workmanship.

The apparatus adapted for practicing the method may comprise a reciprocating plunger operated to deliver blows upon the tread face of the outsole and a horn arranged to support the insole at the point where the blow is delivered by the hammer, means being provided for raising the horn to bring the work into the field of action of the hammer. Preferably the hammer is driven positively and the horn is provided with a yielding mechanism whereby a slight depression of the work is permitted, the pressure of the hammer being adapted to be applied during depression of the support and its release.

25 In the drawing,

Fig. 1 is a side elevation of an apparatus suitable for use in practicing my improved method;

Fig. 2 is a perspective view of an outsole prepared for attachment to a shoe;

Fig. 3 is a perspective view of a shoe prepared to receive the outsole of Fig. 2; and

Fig. 4 is a transverse section through the shoe showing the operating instrumentalities in working position.

30 In practicing my improved method, an outsole 10 is first prepared, as shown in Fig. 2, by roughing the marginal portion 12 of its attaching face and applying thereto cement 14, for example, of the type disclosed in the patent referred to above, or other pressure-responsive cements such as rubber cement or latex cement may be employed.

35 The shoe may be a new shoe, as shown in Fig. 3, or an old shoe, part or all of the sole of which is to be replaced. The overlasted marginal portion 16 of an upper 18 which rests upon an insole 20 is roughened and coated with cement like that on the outsole. After the cement has dried for a short time, the sole 10 is located on the overlasted portion 16 of the upper of the shoe and caused to adhere by pressure of the fingers or a few taps of a hammer. If it is a new shoe, a last 22 is withdrawn and the shoe placed over a horn 24 of the apparatus. The top face of the horn, which is flat, rests against the insole 20 at its marginal portion and directly opposite the horn

is a hammer 26 which is repeatedly reciprocated to cause a localized portion of the outsole 10, the overlasted portion 16 of the upper and the margin of the insole 20 to be forced together, causing the cement between the upper and the sole to provide a strong, permanent bond. In the intervals while the hammer 26 is lifted from the sole, the shoe is moved along so that successive portions of the sole, upper and insole will be subjected to repeated percussional impulses by the action of the hammer.

The apparatus may conveniently comprise a column or frame 28 on the top of which is mounted a motor 30 connected by a belt 32 to a pulley 34 on a shaft 36, the pulley being connected to the shaft by a suitable clutch 38 operated by a rod 40 connected to a treadle 42. The clutch may be of the type known as a pin clutch which, when the operating rod 40 is depressed, will cause the shaft 36 to be rotated continuously and, when the rod 40 is raised, will cause the shaft 36 to stop with the hammer 26 in raised position. A clutch of this type is disclosed in United States Letters Patent No. 958,293, granted May 17, 1910, on application of T. G. Plant. On the front end of the shaft 36 is an eccentric pin 44 which engages a transverse slot formed in a plunger 46 mounted for vertical movement whereby the plunger is caused to be positively reciprocated. The horn 24 has a stem 48 mounted for vertical movement in the frame 28. The stem 48 is hollow and contains a spring 50 the upper end of which rests against a disk 51 which is engaged by a screw 52 threaded in the horn 24. The lower end of the spring rests against the head of a stud 56 which is arranged to slide through a plug 58 threaded into the lower end of the stem 48. Connected to the stud 56 is a block 60 to which is pivoted at 62 an angle lever having arms 64, 66. The arm 64 is connected to a link 68 the lower end of which has a fixed bearing at 70. The arm 66 is connected to the treadle 42 by means of a yieldingly extensible link comprising a rod 72 pivoted to the treadle and a link 74 pivoted to the arm 66. The rod 72 passes freely through an offset 76 on the link 74. A tension spring 78 is confined on the rod between the offset 76 and a nut on the upper end of the rod and is maintained under any desired initial tension by a nut 80 threaded on the rod and engaging the offset 76. Depression of the treadle 42 acts through the yielding link 72, 74 on the arm 66 to straighten the toggle 64, 68, thereby raising the horn 24 toward the hammer 26 and bringing the work into the field of action of the hammer. The spring 50 which supports the horn may be set at any predetermined initial tension by turning the screw 52 and permits the work to yield when the pressure of the hammer exceeds the tension for which the spring is set. After the toggle has been straightened the spring 78 permits further depression of the treadle to

cause the clutch to be tripped and the hammer operated. A treadle spring 82 connected between the treadle and a pin fixed in the frame serves to raise the treadle to insure that the toggle 64, 68 will be broken and the rod 40 raised to disconnect the clutch when the treadle is released.

Having thus described my invention, what I claim as new and desire to secure by Letters Patent of the United States is:

1. That improvement in methods of cement-attaching soles to shoes in which the marginal portion of the upper is lasted inwardly over an insole substantially in parallel relation thereto which consists in applying a pressure-responsive cement to the overlasted margin of the upper and to the attaching face of an outsole, locating the outsole on the bottom of the shoe, and then applying a heavy pressure to different localized areas of the outsole successively about the periphery thereof while supporting the shoe only in each location where the pressure is applied by engagement with the inside foot-engaging surface of the insole to compact the upper materials between the outsole and the insole and to cause adhesion of the outsole to the shoe.
2. That improvement in methods of cement-attaching soles to shoes which consists in locating an outsole on the bottom of a shoe with pressure-responsive cement, supporting different localized areas of the foot-engaging surface of the insole successively about the periphery of the shoe, and subjecting corresponding localized areas of the tread face of the outsole to the action of a power-driven reciprocating hammer to cause the outsole to be secured adhesively to the bottom of the shoe.
3. An apparatus for use in cement-attaching soles to shoes comprising a positively reciprocated hammer having a flat face to engage a substantial area of the marginal portion of the outsole of a shoe, a horn having a flat face to engage a corresponding area of the insole of the shoe opposite to the hammer, a spring supporting the horn, a toggle for raising the horn, and manually operated means for straightening the toggle and controlling the operation of the hammer.
4. An apparatus for use in cement-attaching soles to shoes comprising a positively reciprocated hammer having a flat face to engage a substantial area of the marginal portion of the outsole of a shoe, a horn having a flat face to engage a corresponding area of the insole of the shoe opposite to the hammer, a spring supporting the horn, means for setting the spring at a predetermined initial tension, a toggle for raising the horn, and manually operated means for straightening the toggle to bring the shoe into the field of action of the hammer.
